KITE CONTROL

Kenneth C. Howard, Fort Worth, Tex.

Application May 18, 1951, Serial No. 227,012

3 Claims. (Cl. 244—153)

1

This invention relates to kite controls, and has reference to my copending application Serial No. 168,552, filed June 16, 1950, and now U. S. Patent 2,556,877, issued June 12, 1951.

An object of the invention is to provide a simplified means for increasing the maneuverability of kites.

A particular object of the invention is to provide an inexpensive control for kites whereby the angle of incidence and the lateral center of lift of the kite may be changed at the will of the operator.

These and other objects of the invention will become apparent from the following description and the accompanying drawings, wherein:

Figure 1 is a perspective view of a kite showing a preferred embodiment of the invention attached thereto.

Figure 2 is an enlarged perspective view of the form of the invention illustrated in Figure 1.

Figure 3 is a side elevation of Figure 2.

Figure 4 is a side elevation, similar to Figure 2, of a modified form of the invention.

Figure 5 is a front view of a further modified form of the invention.

The form of the invention shown in Figures 1 through 3 includes a square base 10 having holes 11 in the corners thereof for attaching the outer ends of the bridle strings 12 of a kite 13. The face of the base 10 is provided with a forwardly projecting round spindle 15 having a round centrally located control plate 16 transversely secured to its forward end. The kite string 17 is secured to the base 10 by means of an opening 18 therethrough and a knot 19 formed in the end of the string. The string 17 extends from the base 10, is wound around the spindle 15 so as to detachably engage arcuate notches 20 formed in the rearward periphery of the control plate 16.

In operation, the control unit described is attached to the kite 13 in the manner described on the forward ends of the bridle strings 12. The kite is then flown in the usual manner, preferably with the string 17 in either the uppermost or lowermost notch 20 in the control plate 16 so as to prevent the kite from initially flying to one side or the other. By temporarily releasing and slackening the string 17, the latter unwinds from around the spindle 15. Upon tightening the line 17, the same will likely fit into a different notch 20, thus changing the attitude of the plane of the kite 13 relative to the length of the string 17. Such undeterminable positions, as last referred to, will cause the kite to fly in unpredictable ways, thereby lending interest to

2

the flying. It is to be understood that by repeated operations of slackening and tightening the string, any desired attitude may ultimately be attained.

5 The form of the invention illustrated in Figure 4 is substantially the same as the first described form and includes a flat base 21, spaced holes 22 therearound for engaging the forward ends of the bridle strings 12 of the kite 13, together with a spindle projecting from the center of the base, and a round control plate 24 transversely secured on the forward end of the spindle. There is a collar 25 rotatably mounted on the forward end of the spindle 23 and has a laterally projecting spring 26 which does not normally contact the periphery of the plate 24. The outer end of the spring 26, which projects outwardly beyond the control plate 24, is provided with an eye 27, for slidably receiving the kite string 17, which, as before, is wound around the spindle 23 and is secured to the base 21 by passing through an opening 28 and terminating in a knot 29 on the back side of said plate. A projecting pin 30 is positioned through the spindle 23 for locating the collar 25 in its described position. When the string 17 is taut, the spring 26 engages one of a series of spaced notches 31 around the inner periphery of the plate 24. Preferably, the notches 31 are smaller and spaced closer together than those 20, shown in Figure 3, and whereby there is a greater fineness of adjustment.

35 The operation of the last described form of the invention is substantially the same as described in connection with the first form, but differs therefrom in that the spring 26 engages the notches 31 instead of the string 17 engaging the notches 20. The spring 26 readily disengages the notches 31 when the string 17 is slackened, and readily engages the same notches when the string is taut, thereby lending to a positive engagement positioning the string at some location around the periphery of the control plate 24.

40 The form of the invention illustrated in Figure 5 is very similar to the first described form of the invention and includes a square plate 32 having holes 33 in the corners thereof for engaging the forward ends of the bridle strings 12 of the kite 13. This form of the invention includes a forwardly projecting spindle 34 and an irregularly shaped control plate 35 on the forward end of the spindle. As before, the string 17 is wound around the spindle 34 and secured to the plate 32. Notches in the inner or rearward periphery of the plate 35 engage the string 17 when the latter is 45 taut, and releases the same when the string is

temporarily slackened. All described forms of the invention provide for changing the relative center of lift, and consequently changes the attitude of the plane of the kite 13 relative to the length of the string 17 for increasing the interest in flying the kite.

The described forms of the invention may be made in many ways within the scope of the appended claims.

What is claimed is:

1. A kite control comprising a base adapted to be attached to the forward ends of the kite's bridle strings, a spindle projecting forwardly from said base, a control plate transversely secured on the forward end of said spindle, notches in the rearward periphery of said control plate for engaging the kite string when the latter is secured to said base and wound around said spindle and positioned against the said plate.

2. A kite control comprising a base adapted to be attached to the forward ends of the kite's bridle strings, a spindle projecting forwardly from said base, a control plate transversely secured on the forward end of said spindle, notches in the rearward periphery of said control plate, a collar

5 rotatably mounted on said spindle adjacent said control plate, a laterally projecting spring mounted on said collar and extending outwardly beyond the periphery of said control plate, notches in the rearward periphery of said control plate and adapted to engage said spring, and an eye in the outer end of said spring and adapted to slidably receive the string of the kite when said string is secured to said base and wound around said spindle.

10 3. A kite control as defined in claim 1, and wherein the periphery of the control plate is of an irregular shape.

KENNETH C. HOWARD.
